Primary Examiner — Vy N Koenig(74) Attorney, Agent, or Firm — Boyle Fredrickson, S.C.(57) CLAIM

The ornamental design for a packaging for fragrance bottle, as shown and described.

DESCRIPTION

FIG. 1 is a front perspective view of a packaging for fragrance bottle showing our new design;

FIG. 2 is a front view of the packaging of FIG. 1;

FIG. 3 is a rear side view of the packaging of FIG. 1;

FIG. 4 is right side view of the packaging of FIG. 1;

FIG. 5 is a left side view of the packaging of FIG. 1;

FIG. 6 is a top view of the packaging of FIG. 1; and,

FIG. 7 is a front perspective view of the packaging of FIG. 1, shown in an open position.

The evenly dashed broken lines in the drawings depict surface treatment of the packaging which form no part of the claimed design.
